RAIL JOINT

Charles D. Barrett, Altoona, Pa.

Application March 30, 1937, Serial No. 133,792

7 Claims. (Cl. 238—243)

This invention relates to rail joints; and it has reference more especially to what are ordinarily known as splice joints for railway track rails.

With existence of differences in the fishing height of the contiguous ends of adjoining track rail sections due either to inaccuracies of manufacture initially or to wear from use, it is virtually impossible to draw up joint bars of ordinary construction for attainment of firm and rigid support of the rail heads at the region of the split. As a consequence, both lateral and vertical play is permitted between the rail ends. Such looseness, even though small at the beginning, becomes more and more pronounced in a short time under the continuous pounding of the wheels of moving trains, particularly in tracks assigned to high speed service, with attendant rapid wear both of the joint bars and the rails.

The chief aim of my invention is to overcome the above drawbacks with a view toward reducing the high cost of track maintenance. This desideratum I realize in practice as hereinafter more fully disclosed through provision of a splice joint wherein the lower edge of the joint bar at one side clears the base flange of one of the adjoining rail sections adjacent the split and the lower edge of the joint bar at the other side clears the base flange of the other rail section adjacent the split, and wherein the bars are otherwise so configured for capacity to bend and flex incident to being drawn up so that their upper edges are brought into firm engagement with the undersides of the rail heads in the region of the split. Thus, in this way, the heads of the contiguous rails are afforded effective rigid support, and the joint fortified against the subsequent development of looseness by which its strength and efficiency is impaired.

Another object of my invention is to secure the foregoing advantages with joint bars which are exact duplicates and adapted for use in reversed positions relative to each other at opposite sides of the joint.

Other objects and advantages will appear from the following detailed description of the attached drawings, wherein

Fig. I is a view partly in plan and partly in plan section of a rail joint conveniently embodying my invention in one form.

Fig. II shows the rail joint of Fig. I in side elevation.

Fig. III is a fragmentary longitudinal section view of the joint taken as indicated by the arrows III—III in Figs. I and IV.

Figs. IV, V, VI and VII are cross sectional views

of the joint respectively taken as indicated by the arrows IV—IV, V—V, VI—VI, and VII—VII in Fig. II.

Figs. VIII and IX are diagrammatic views of one of the splice bars of the joint showing the reaction of the joint bars under load.

Figs. X, XI and XII are views corresponding to Figs. I, II, and III showing an alternative form of my improved track rail joint.

Fig. XIII is a cross sectional view taken as indicated by the arrows XIII—XIII in Fig. XI; and

Figs. XIV and XV are diagrammatic views corresponding to Figs. VIII and IX showing the reaction of the joint bars of the alternative embodiment under load.

In the form of my invention shown in Figs. I—VII, the contiguous ends of the adjoining track rail sections 1 and 2 are connected by splice bars 3 and 4 which overlap the split 5 at opposite sides 20 of the rail, and which are drawn into the fishing spaces of the rail sections by a number of longitudinally-spaced transversely positioned headed screw bolts 6 with associated nuts 7 and lock washers 8. The splice bars 3 and 4 may have 25 the general cross sectional configuration shown in Figs. IV—VII to conform with the fishing spaces of the rails, and, in accordance with my invention are made exact counterparts of each other with the following distinguishing characteristics:

Each bar 3, 4 is formed with an upper medial bearing 9 which is symmetrical in respect to the longitudinal center of the bar, top end bearings 13, 14, a bottom medial bearing 15 which is substantially half as long as the top medial bearing and wholly disposed to one side of the longitudinal center of the bar, see Figs. II and III, and with bottom end bearings 16 and 17 corresponding to the top end bearings 13, 14, all of said top and bottom bearings being sloped to correspond respectively with the under surfaces of the rail heads 11 and 12 and the upper surfaces of the rail base flanges 18, 19. With the splice bars 3, 4 arranged and assembled in the joint as shown, it will be 40 noted from Fig. II that the bottom medial bearing 15 of the bar 3 rests only on the bottom flange 18 of the rail section 1 immediately adjacent the split 5 to the left of the latter, and, from Fig. III, that the bottom medial bearing 15 of the bar 4 rests only on the base flange 19 of the rail section 2 immediately adjacent the split to the right of the latter. Due to upward offsets 20, 21 in the lower edges of the bars 3, 4 and the clearance thus formed above the base flanges 18, 19 55

of the rail sections 2 and 1 respectively at opposite sides of the split 5, said bars are free to bend and flex compensatively, i. e., to torsionally bend under the drawing action of the bolts 6, the 5 lateral bending of the bars being facilitated by virtue of the downward offsets 22, 23 and 24 respectively and the resulting clearances intervening the upper medial and end bearings 9 and 13, 14 and the lower medial and end bearings 10 15 and 16. As a consequence of such bending and flexing of the bars 3, 4, the upper medial bearings 9 are urged into effective intimate contact with the undersides of the heads 11, 12 of the contiguous rail sections immediately adjacent 15 the split 5 at opposite sides of the latter, irrespective of differences in the fishing height of said sections. It therefore follows that with joint bars 3, 4 constructed after the manner described, not only are the ends of the rail heads 20 11, 12 of the joining rail sections 1, 2 firmly supported and accurately aligned, but the joint fortified against the development of looseness and wear of the bars and the rails incident to the use of the track. Fig. VIII shows that the 25 centroids of pressure for positive bending of one of the joint bars under load are located similarly to those of the usual form of joint bars. For negative bending of the bar, see Fig. IX, the pressure on the base near the center will be higher 30 than in ordinary forms of joint bars, but nevertheless full bending moment will obviously be developed in both bars of the joint.

In the alternative form of my rail joint shown in Figs. X-XV, the bars 3a, 4a are identical with 35 the bars 3, 4 of the first described embodiment except for the omission of the bottom end bearings 17 and the substitution therefor of wedges 25. As shown, the wedges 25 are urged inward by pressure plates 26 under the drawing action 40 of the endmost bolts of the series 6a, see Fig. XIII, more particularly. By means of the wedges 25, adjustment can be made for differences in the fishing height of the rail sections 1a, 2a at the outer ends of the bars 3a, 4a. From Figs. XIV, 45 XV, it will be seen that the action of the bars of the modified form of my invention under load is exactly the same as that of the bars of the first form. In order to preclude the necessity for repetitive description, all other features not 50 specifically referred to in connection with Figs. X-XV but having their duplicates in the first described embodiment of my invention, have been identified with the same reference numerals previously employed to each of which the letter *a* has 55 been added for the purposes of distinction.

Having thus described my invention, I claim:

1. In a track joint, integrally-formed counterpart joint bars adapted to be placed in reversed relation end for end in the fishing spaces at opposite sides of contiguous rail sections, each joint bar having a top bearing surface for supporting the end portions of the heads of both rail sections across the split of the joint, a bottom bearing to one side of the split for engaging the base flange of one rail section immediately adjacent the split, an upward offset clearing the base flange of other rail section immediately adjacent the split, and a bearing for engaging the base of the last mentioned rail section spaced from the split on the side of the bar having the upward offset, so that inaccuracies in the vertical dimensions of the fishing spaces of the two rail sections may be compensated for and both bars drawn up tight into said spaces; and securing 70 means for drawing the bars into the fishing spaces.

2. In a track joint, integrally-formed counterpart joint bars adapted to be placed in reversed relation end for end in the fishing spaces at opposite sides of contiguous rail sections, each joint bar having a top bearing surface for supporting the end portions of the heads of both rail sections across the split of the joint, a medial bottom bearing to one side of the split for engaging the base flange of one rail section immediately adjacent the split, an upward offset clearing the base flange of the other rail section immediately adjacent the split, top bearings at opposite ends for engaging the heads of the respective rail sections, and a bottom bearing at the end of the portion on the side having the upward offset for 10 engaging the base flange of the corresponding rail section, so that inaccuracies in the vertical dimensions of the fishing spaces of the two rail sections may be compensated for and both bars drawn up tight into said spaces; and securing 20 means for drawing the bars into the fishing spaces.

3. In a track joint, integrally formed counterpart joint bars adapted to be placed in reversed relation end for end in the fishing spaces at opposite sides of contiguous rail sections, each joint bar having a top bearing surface for supporting the end portions of the heads of both rail sections across the split of the joint, a medial bottom bearing to one side of the split for engaging the base flange of one rail section immediately adjacent the split, an upward offset clearing the base flange of the other rail section immediately adjacent the split, and bottom bearings at opposite ends for engaging the base flanges of the respective rail sections, so that inaccuracies in the vertical dimensions of the fishing spaces of the two rail sections may be compensated for and both bars drawn up tight into said spaces; and a securing 25 means for drawing bars into the fishing spaces.

4. In a track joint, integrally-formed counterpart joint bars adapted to be placed in reversed relation end for end in the fishing spaces at opposite sides of contiguous rail sections, each joint bar having a medial top bearing for supporting the end portions of the heads of the rail sections across the split of the joint, a medial bottom bearing to one side of the split for engaging the base flange of one rail section immediately adjacent the split, an upward offset clearing the base flange of the other rail section immediately adjacent the split, and top and bottom bearings at opposite ends for respectively engaging the heads and the base flanges of the two rail sections, so that inaccuracies in the vertical dimensions of the fishing spaces of the two rail sections may be compensated for and both bars drawn up tight into said spaces, and securing means for drawing the bars into the fishing spaces.

5. In a track joint, integrally-formed counterpart joint bars adapted to be placed in reversed relation end for end in the fishing spaces at opposite sides of contiguous rail sections, each joint bar having a medial top bearing for supporting the end portions of the heads of the rail sections across the split of the joint, a medial bottom bearing to one side of the split for engaging the base flange of one rail section immediately adjacent the split, an upward offset clearing the base flange of the other rail section immediately adjacent the split, end top bearings for engaging the heads of the respective rail sections, a bottom end bearing on the portion having the medial bottom bearing; a wedge for engaging between the end of the portion having the upward offset 70

and the flange of the corresponding rail section; securing means for drawing the two bars up tight into the fishing spaces; and separate securing means for drawing the wedges.

5 6. A track joint according to claim 1, in which the securing means comprises a plurality of longitudinally spaced draw bolts which pass through registering openings in the joint bars and in the webs of the rail sections.

10 7. An integrally formed joint bar for track

joints having top and bottom bearing surfaces respectively at each end, a top medial bearing surface symmetrically disposed in respect to the transverse central plane of the bar, a bottom medial bearing surface offset to one side of the transverse plane, and upward clearance recessions in the longitudinal intervals between the bottom end bearings and the bottom medial bearing.

CHARLES D. BARRETT. 10
